UNITED STATES PATENT OFFICE.

HAROLD F. ELLIOTT, OF PALO ALTO, CALIFORNIA, ASSIGNOR, BY MESNE ASSIGNMENTS, TO FEDERAL TELEGRAPH COMPANY, OF SAN FRANCISCO, CALIFORNIA, A CORPORATION OF CALIFORNIA.

ARC CONVERTER.

Application filed December 14, 1921. Serial No. 522,336.

To all whom it may concern:

Be it known that I, HAROLD F. ELLIOTT, a citizen of the United States, and a resident of Palo Alto, in the county of Santa Clara 5 and State of California, have invented a new and useful Arc Converter, of which the following is a specification.

My invention relates to the operation of arc converters, such as the Poulsen arc, used 10 for converting electrical energy in the form of direct current or low frequency alternating current, into electrical energy in the form of radio frequency current. More particularly my invention relates to an arc converter which is operated in an atmosphere of 15 hydrogen or other gas having similar electro-mechanical properties.

The operation of such arcs is more satisfactory when pure gas such as hydrogen is 20 used, undiluted by other gases. Not only are the operating characteristics of the arc impaired, but explosions may also result when air or oxygen is commingled with the hydrogen. The harmful mixture may be 25 brought about at the time the arc chamber is filled with hydrogen preparatory to its operation or after an old charge of the gas is expelled, since the chamber, if no extra 30 precautions be taken, usually has left in it, prior to refilling, a small amount of air. It is one of the objects of my invention to 35 obviate such an occurrence, and thereby to insure efficient and safe operation. Another object is to make it possible to maintain the arc chamber clean and free from any carbon deposit.

The invention possesses other advantageous features, some of which, with the foregoing, will be set forth at length in the 40 following description, where I shall outline in full that form of the invention which I have selected for illustration in the drawing accompanying and forming part of the present specification. In the drawing I have 45 shown one embodiment of my invention, but it is to be understood that I do not limit myself to that form, since the invention as expressed in the claims may be embodied in other forms as well.

50 The single figure illustrates diagrammatically an apparatus embodying my invention. The arc chamber or container 1 is preferably cast and made with a jacket 2 for the accommodation of cooling water. The

interior 3 of the chamber 1 holds the hydrogen or other gas and accommodates the electrodes 5. Magnetic field poles 4 projecting through the sides of the chamber 1 influence the arc in a well-known manner. The gaskets 6 serve to render the enclosure 55 gas-tight.

Means are provided for pumping out the used gas and supplying new gas to the interior 3 of the chamber. Thus the piping 7 connects the chamber with a vacuum pump 65 9. During the process of exhaustion by this pump, the chamber is not in communication with any external gas source. For effecting this, the pipe 8 which connects the chamber with a gas reservoir 17, is provided with a 70 valve 16. This valve is kept closed while pump 9 is exhausting. All connections to the chamber must of course be gas tight. In order to prevent excessive pressures within the chamber during operation, a poppet 75 valve or relief valve 15 is provided somewhere in the pipe 7. A combined pressure and vacuum gauge 14 indicates how far the exhaustion is carried, and after a sufficiently good vacuum is obtained, the pump 9 may 80 be rendered inactive. Then the valve 10 may be turned to disconnect the pump 9 from the pipe 7 and to close up the end of this pipe so as to make the chamber air 85 tight.

A surge chamber 12 connected to pipe 7 through a valve 13 is shown, and serves as a reservoir to prevent large variations in pressure which would otherwise result from the variations in temperature attendant upon the starting and stopping of the arc. An alternate device for effecting this result is also shown, consisting of a gas seal 19 connected to a pipe 7 through the valve 18. This form may be used for 90 operating the arc with an envelop of gas at atmospheric pressure. The gas seal 19 is formed with an up-standing goose neck portion and preferably the volume of this seal should be large enough to serve also 100 as a surge chamber. The operation and construction of such a device is described and claimed in a pending application in the name of Ralph R. Beal, entitled Arc converters, Serial No. 402,928, filed August 11, 1920.

Upon operation of the arc for a long period there is a tendency for a carbon de-

posit in the form of soot to accumulate. To clean this accumulation out expeditiously, I provide a blower 11 or its equivalent, which may be connected to pipe 7 by turning valve 10. The door of the arc chamber may be opened after such a period of operation, and the blower operated for a short time. The soot may then easily be removed. After this is accomplished, the chamber may 10 be closed and the pump 9 used to exhaust all of the air.

The mode of operation of the invention may now be made more apparent. If there is any deposit which it is desired to clean out, valve 10 is turned to connect blower 11 with pipe 7, valves 15, 16, 13 and 18 are closed; the door of the arc chamber 1 is opened, and the blower 11 is operated until all the soot or other deposit is blown out. Then blower 11 is stopped, the door of the chamber is closed, valves 16 and 18 remain closed, and valve 10 turned to the position shown so as to connect pump 10 to the chamber. The pump is then operated until a sufficient degree of vacuum is obtained, after which the pump is stopped. Valve 10 may then be turned to shut the end of pipe 7, and valve 16 opened to fill the chamber 1 with gas from a source 17, until sufficient pressure is obtained. During the process of exhaustion, valve 13 should be either open or closed, depending upon whether the chamber 12 contains air or diluted gas; or whether it already con-

tains hydrogen. During ordinary operation of the arc, it is preferable to use the surge chamber 12 instead of the gas seal 19.

I claim:

1. In an arc converter, an arc chamber, a pump for exhausting the chamber, a blower, and a single means arranged to connect either the pump or blower with the arc chamber.

2. In an arc converter, an arc chamber, a pump for exhausting the chamber, a blower, and a valve arranged so as to place either the blower or the pump in connection with the chamber.

3. In an arc converter, an arc chamber, a pump for exhausting the chamber, a blower, and a valve so arranged that it may seal the chamber or else connect either the blower or the pump thereto.

4. In an arc converter, an arc chamber, a pipe leading from the arc chamber, a pair of branch pipes connected to said pipe, said branches connecting to the pipe at a common point, a pump for exhausting the chamber connected to one of the branches, a blower connected to the other, and a valve located at the common point and adapted to connect either of the branches with the pipe leading from the arc chamber.

In testimony whereof, I have hereunto set my hand.

HAROLD F. ELLIOTT.
